HAIR CURLER

Nell Fulton, New York, N. Y.

Application August 11, 1933, Serial No. 684,725

11 Claims. (Cl. 132—38)

The present invention relates to hair curlers, and has for an object to provide a hair curler with a body portion which may be of flexible material and also of material which may be destroyed, such as paper, and to provide the body portion with a securing, rolling and holding device detachably connected to the body portion so that the latter may be readily substituted on the rolling device.

10 The present application constitutes a continuation in part of my prior application, Serial No. 649,028, filed December 27, 1932, for a Hair curler.

Another object of the present invention is to provide a hair curler which may be made of absorbent material so as to assist in the drying of the hair by absorbing moisture therefrom.

15 The invention further aims to provide a hair curler which may be used by professional hair dressers, or for individual private use and where-
20 in the flexible body portions may be supplied in multiple, such as in pad form, and to provide a body portion which may be produced from a single blank in one piece and provided with the necessary means not only of enclosing a lock of hair, but also with the necessary cooperating
25 means for the temporary attachment of the rolling and holding device which is used so that these rolling or holding devices may be purchased in relatively small quantities and used contin-
30 uously with any desired number of flexible body portions.

The invention also provides improved means for not only rolling the body portions with the lock of hair therein, but also of improved means
35 for securing these devices temporarily to the body portion and for subsequently securing the device in rolled position in place whether the curler is rolled inwardly or outwardly with refer-
ence to the side of the head.

40 Another and important object of this invention is to provide a separable flexible body part and rolling device and holder by use of which the curler may be rolled, with a lock of hair therein and held in rolled position for a desired period
45 of time to set the hair when the rolling and holding device may be removed by sliding it endwise from the rolled curler; the set hair and body part having sufficient stiffness to substantially remain in rolled position. The rolling device may be
50 removed at any time after the rolling operation.

With the foregoing and other objects in view, the invention will be more fully described herein-
after, and will be more particularly pointed out in the claims appended hereto.

55 In the drawings, wherein like symbols refer to

like or corresponding parts throughout the several views,

Figure 1 is a perspective view of a hair curler embodying the features of the present invention and in the first position of application to the 5 hair, the dotted lines showing a lock of hair.

Figure 2 is a like view with the curler in applied position ready for rolling.

Figure 3 is a detail top edge view of one form of clamping or holding device for initially retaining 10 the curler on the hair during rolling.

Figure 4 is a perspective view of the curler as applied and clamped on the hair, the view being obverse to Figure 2.

Figure 5 is a fragmentary upper edge view 15 of the folded curler with the temporary holding device in position thereon.

Figure 6 is a perspective view of a slightly modified form of hair curler.

Figure 7 is a sectional view taken through a 20 hair curler showing a modified form of clamp applied thereto.

Figure 8 is a plan view of the clamp of Figure 7 in open position.

Figure 9 is a perspective view of another modified form of hair curler having modified form of clamp applied thereto. 25

Figure 10 is a transverse section taken through the end of the same.

Figure 11 is a side elevation of another modified form of curler. 30

Figure 12 is an edge view of the same.

Figure 13 is a perspective view of the modified form shown in Figures 11 and 12.

Figure 14 is a side elevation of another modified 35 form of hair curler.

Figure 15 is an enlarged longitudinal section-
al view taken through the same on the line
15—15 of Figure 14.

Figure 16 is a perspective view of a further 40 modified form of the curler.

Figure 17 is a longitudinal section therethrough on the line 17—17.

Figure 18 is a perspective view of a further 45 modified form of the curler, the dotted lines showing the blank in flat position before bending.

Figure 19 is a longitudinal sectional view there-
of on the line 19—19.

Figure 20 is a perspective view of another modified form of the curler, the dotted and full lines showing the initial and folded positions of the parts thereof. 50

Figure 21 is a fragmentary perspective view of the upper end of a curler applied to the hair 55

and showing a further modification of the curler and the clamp.

Figure 22 is an upper edge view of the same, and,

5 Figure 23 is an inner or handle end view of the three arm clamp of Figure 21.

Referring now to the drawings, and first to the construction shown in Figures 1 to 5, the hair curler comprises a body portion 25 which may be 10 of any suitable configuration and which is disclosed as being substantially rectangular and elongated in one direction. Toward one end, the body portion 25 has at one edge a flap 26 preferably integral with the body portion and 15 which is proportioned to overlap to at least a considerable extent against one side of said end of the body portion to enclose an interposed lock of hair 27, as shown to advantage in Figures 2 and 4. The lower end of the body portion 25 is in the form of a tongue equipped with means, 20 either integral or otherwise, for detachably engaging a rolling and holding or retaining member 28. The member 28 may be in the form of a length of wire of one or more strands suitably covered, and which is bendable with sufficient resistance to 25 retain its shape for use, as shown. The lower end of the body portion 25 is rolled a suitable number of times about the wire 28, and is then held thereto by a spring clip 29 readily removable so that after use the body portion 25 may be interchanged upon the wire 28.

According to the present invention, means is 30 provided for initially clamping the curler to the lock of hair 27 so that the two hands may be employed for rolling the curler to the desired tightness, the clamping means being readily removable, so that when the curler is rolled up to the clamp the latter may be removed without disturbing the position of the curler.

40 To carry out this feature of the invention, the body portion 25 may have a pair of transversely spaced apart slots 30 therein for the reception of a prong or jaw 31 of a clamp, shown in detail in Figure 3, so that the prong 31 may be threaded 45 through the slots 30 so as to lie against the outer side of the curler, while the opposite prong or jaw 32 may engage across the opposite outer side of the curler, as shown in Figure 5. The prong 31 which is not threaded through the curler is 50 preferably provided with a weight 33 on its outer end so as to balance the weight of the handles 34 which are disposed on the inner end of the clamp and pivotally connected together at 35.

With this form of the invention, the clamp is 55 held by the handles 34 which are compressed so as to spread the prongs 31 and 32 into open or diverging position. The prong 31 is shorter than the prong 32, and is adapted to be threaded through the slots 30 in such wise as to engage 60 across the back of the body portion 25 near the upper end thereof. The curler may thus be supported by the clamp and the latter manipulated with one hand to press the body portion 25 of the curler in place against the rear side of 65 the lock of hair 27. The flap 26 is now folded over on the lock of hair, and the pressure on the handles 34 relieved so that the spring 36 of the clamp urges the prongs 31 and 32 together to bind the folded body portion on the lock of hair 27. The curler may thus hang from the lock of hair and is supported thereby so that the rolling device 28 may be manipulated to roll the curler up about and with the lock of hair.

70 When the curler is rolled to its upper end, the clamp may be readily withdrawn by a slight pres-

sure on the handles 34 and retracting the prong 31 from the slots 30.

The modification shown in Figure 6 comprises a body portion 37 which may be in one piece without flaps, and which may have slots 38 at 5 its upper end for the reception of a prong or jaw of a clamping member. The lower end of the body portion 37 is provided with a series of transversely spaced apart slots 39, and the slotted portion is overturned, as shown, for reinforcing the 10 lower end of the body portion and supporting a rolling and holding device 40. The device 40 may comprise a single length of wire overturned upon itself and twisted to form a handle 41. One end 15 of the wire may be overturned against the rear side of the body portion 37 to hold the latter folded, while the opposite free end may project outwardly to provide a hand hold opposite to the handle 41. The body portion of all of the forms 20 of this invention may be made of any suitable material capable of being rolled. They may be made of paper which is absorbent so as to assist in drying the hair and also which may be discarded or thrown away after each use because the construction is such that the clamp is detachable 25 and also the rolling and holding device is detachable, as shown at 28 and 40 in Figures 1 and 6.

In Figure 7, a modified form of clamp is shown in connection with the form of Figure 6. In this instance, the clamp shown in detail in Figure 8, 30 comprises a long prong 42 which, in this instance, may be threaded through the slots 38.

Pivoted at 43 on the inner end of the prong 42 is an outer short prong 44, the latter having a 35 spring tongue 45 at its inner end adapted to snap against the inner end of the prong 42 for yieldably holding the clamp in closed position. The clamp is opened, as shown in Figure 8, so that the short prong 44 serves as a handle for positioning the long prong 42 in the slots 38. The short prong 40 44 is then merely overturned so that it will snap against the opposite side of the curler and clamp it in binding position.

In the modified form shown in Figures 9 and 10, the body portion 46 of the curler is provided with 45 spaced slots 47 near its upper end, and at one edge has a flap 48 adapted to be overturned against the inner face of the body portion 46 to enclose a lock of hair. The flap 48 has a slot 49 50 therein. The lower end of the body portion 46 has a pair of slots 50 transversely spaced apart to detachably receive a rolling and holding device 55 of any construction such as shown in Figure 6.

The clamp shown in Figures 9 and 10 comprises 55 a pair of flat prongs 51 and 52 which are preferably flared slightly at their outer ends, as at 53, for ease of insertion in the slots 47 and 49. The inner ends of the prongs 51 and 52 have overturned flanges 54 at their longitudinal edges which bind upon the opposite edge portions of 60 a U-shaped flat spring 55 normally urged to expanded position, as shown in Figure 10, to hold the prongs 51 and 52 together.

The spring 55 also interconnects the prongs and acts as a substitute for the usual pivot. Of 65 course, any suitable construction of clamp may be used. The inner ends of the prongs 51 provide handles 56 by means of which the prongs may be spread and supported.

In the form shown in Figures 11 and 12, the 70 body portion 57 comprises merely a length of suitable material overturned upon itself to provide two thicknesses or walls between which the lock of hair may be engaged. One wall is provided with a pair of transversely spaced apart slots 58 75

which are offset in an edgewise direction with respect to correspondingly formed slots 59 provided in the opposite end portion of the body 57. These slots 58 and 59 are offset to facilitate the insertion of the prongs 51 and 52 of the clamp of Figures 9 and 10, or of the prongs of any other suitable type of clamp. The lower end of the body portion 57 may be provided with registering pairs of slots for detachably receiving the rolling and holding member as above described. The curler in Figures 11 and 12 is shown in partly open position for receiving a lock of hair and also in position for admitting of the quick and easy threading of the opposite prongs of the clamp through the slots 58 and 59.

Figures 14 and 15 show another modified form of the curler wherein the body portion 61 is overturned upon itself to provide opposite sides of equal length.

It will be noted that one side 62 is of greater width than the other side. The upper ends of both sides of the curler are overturned upon themselves to provide hem 63, and the same are foreshortened with respect to stepped edges of the sides of the curler, as shown in Figure 14, and with their ends beveled or inclined as at 64 to facilitate the insertion of the opposite prongs of a suitable clamping device. The lower end of the body 61 may have slots 65 therein for detachably receiving a rolling and holding device.

A further modification of this invention is shown in Figures 16 and 17 wherein the body portion is overturned upon itself to provide a long side 66 and a short side 67. The long side 66 may have slots 68 therein to receive a prong of a clamp, and the overturned lower end of the short side 67 of the body may have spaced slots 69 for detachably receiving therethrough a combined rolling and holding device 70. The holding device 70 may comprise a single length of wire overturned upon itself and twisted to provide a handle at its closed end and a long prong or arm 71 and a short prong or arm 72. The long arm 71 is threaded through the slots 69, while the short arm 72 bears against the outer side of the body portion to assist in rolling the same.

The modification shown in Figures 18 and 19 embodies a body portion 73 provided with clamp receiving slots 74 in its upper end and an overturned slotted portion 75 at its lower end for detachably receiving a rolling and holding device.

At one edge, the body portion 73 has a flap 76 intermediate the ends of the body portion and which is adapted to be folded over against the outer side of the body portion 73 to engage a lock of hair therebetween. This flap 76 is preferably provided with outwardly tapering opposite edges 77 as shown in Figure 18.

In the form shown in Figure 20, the body portion 78 has the upper clamp receiving slots 79 and the lower slots 80 in its overturned portion to detachably receive the rolling and holding device. Intermediate the upper and lower ends of the body portion 78 is provided at its opposite lateral edges a pair of flaps 81 with outwardly converging edges 82, and which are arranged to substantially meet at the medial part of the body 78, as shown in Figure 20. These flaps 81 are adapted to engage and hold a lock of hair against the body portion 78.

The modified construction illustrated in Figures 21, 22 and 23 is adapted for use particularly with the body portion 83 of single thickness and which is unslotted, but provided with a side adapted for engagement with a clamp. The clamp for

use with the body portion 83 comprises a central arm 84 and a rear arm 85 and a front arm 86. The inner ends of the rear and front arms 85 and 86 are flared outwardly away from the inner end of the central arm 84, as shown in Figure 22. Preferably the inner end of the central arm 84 is of greater length than the adjacent ends of the rear and front arms 85 and 86 so as to provide a long handle for the central arm which may cooperate with the opposite handles one at a time.

A combined spring and supporting member 87 is overturned upon itself and engages the opposite sides of the central handle and is held thereto by overturned lugs or flanges 88 on the central handle and at opposite sides thereof as shown. The opposite ends of the spring member 87 are held at an angle and lie against the inner faces of the short handles and are secured thereto by overturned flanges 89. The rear arm 85 has preferably a roughened or milled inner face 90 adapted to engage across the rear side of the body portion 83 of the curler and preferably carries a weight 91 on its outer end to counterbalance the weight of the handles. The central or middle jaw 84 is normally urged by the spring member 87 toward the rear arm or jaw 85 and is adapted to clamp across the outer face of the body portion 83 of the curler, so that the curler is supported at its upper end between the rear and middle arms of the clamps. The device may thus be applied to a lock of hair 92 as shown in Figures 21 and 22. The lock of hair 92 is engaged over the outer side of the middle arm 84 and the front arm or jaw 86 is then released so as to bind against the lock of hair and hold it in proper position against the body portion 83. When the lower end of the curler is rolled up to the clamp, pressure is then exerted upon the opposite small handles so as to spread the rear and front jaws 85 and 86 away from the middle jaw 84. The clamp may thus be easily withdrawn both from the lock of hair and the body portion of the curler.

It is apparent that by engaging the thumb against the long handle and a finger against the rear short handle, the rear jaw 85 may be opened for receiving the body portion 83 of the curler. The device may now be grasped by engaging the finger with the middle handle and the thumb with the front jaw handle to compress the handles and open the front jaw 86. In thus holding the device, it may be slipped in beneath the lock of hair 92 and with the front jaw at the front of the lock of the hair. By releasing the front jaw handle the latter is now urged against the lock of hair 92 for holding the device in suspended relation from the lock of hair.

It is obvious that various changes and modifications may be made in the details of construction and design of the above specifically described embodiment of this invention without departing from the spirit thereof, such changes and modifications being restricted only by the scope of the following claims:

What is claimed is:—

1. A hair curler comprising a flexible body portion adapted to be folded upon itself to encase a lock of hair, a holding device having a pair of pivotally connected spring pressed jaws adapted to be engaged against the opposite sides of the body portion for normally closing the same, said body portion having slots in one wall thereof for receiving in threaded relation one of said jaws and the other jaw having a counterweight on its free end for counterbalancing the clamping mem- 70 75

ber on the curler, and a rolling device detachably connected to the lower end of the curler for rolling the same while held by the holding device.

5 2. A hair curler, comprising a flexible body portion adapted to be folded upon itself to encase a lock of hair, a holding device having a pair of connected jaws normally urged toward each other and adapted to be engaged against opposite sides of the folded body portion near the upper end thereof for normally closing the same, said body portion having a slot in its wall for receiving one jaw threaded therethrough, a counterweight on the free end of the other jaw, and a rolling device mounted on the lower end of the body portion for rolling the same while held by the holding device.

10 3. A hair curler, comprising a flexible body portion, a rolling device on the lower end of the body portion for rolling the same in the hair, said body portion having openings in its upper end, and a yielding hair clamp having opposed arms with one arm shorter than the other arm to facilitate threading of one arm through the openings in the body portion for clamping hair thereto during the rolling operation.

15 4. A hair curler, comprising a flexible body portion having openings in its upper end, and a clamping device for holding the upper end of the body portion to the hair during rolling, said clamping device having long and short clamping arms to facilitate threading one of the arms through the openings in the body portion to retain the latter against slipping during rolling.

20 5. A hair curler, comprising a flexible body portion having openings in its upper end, and a clamping device for holding the upper end of the body portion to the hair during rolling, said clamping device having long and short clamping arms with a counterweight on the long arm, the short arm adapted for threaded engagement in said openings of the body portion to hold the same against slipping during the rolling operation.

25 6. A hair curler, comprising a flexible body portion having openings in its upper end, and a clamping device for holding the upper end of the body portion to the hair during rolling, said clamping device having long and short arms pivotally connected together and having diverging handles thereon beyond the pivot for spreading the arms and opening the clamping device, a counterweight on the free end of the long arm, the short arm adapted to be threaded through the openings in the body portion to hold the clamp thereto.

30 55 7. A hair curler, comprising a flexible body

portion adapted to be rolled in the hair, and a clamping device having opposed arms to engage the opposite sides of the body portion and hold the same against a lock of hair, said body portion having an opening therein spaced from the edge of the body portion to guide and facilitate the insertion of an arm of the clamping device in the opening.

5 10 8. A hair curler, comprising a flexible body portion having opposite wall members adapted to engage the opposite sides of a lock of hair, a wall member having an opening therein, and a clamping device having clamping arms adapted to engage the wall members to press the same against the lock of hair, an arm of the clamping device adapted to engage in said opening to facilitate spreading of the wall members when the clamping arms are opened and to hold the body portion to the clamp when open.

15 9. A hair curler, comprising a flexible body portion having a wall adapted to engage a lock of hair and having an opening in the wall, and a clamping device having a pair of clamping arms movably connected together at one end, one arm adapted to engage in the opening of the body wall, said arms having supporting handles diverging from the connected ends of the arms and adapted to be squeezed together for releasing the arms from pressure on the flexible body.

20 10. A hair curler comprising a flexible body portion adapted to be rolled from its lower end in the hair and having a threading structure at its upper end, and a hair clamp having hingedly connected arms for clamping the upper end of the flexible body portion against the hair, an arm of the clamp adapted to be threaded through said threading structure for suspending the flexible body portion from the clamp and prevent downward slipping of the body portion from the hair when the clamp is closed on the hair and for holding the body portion on the clamp when open during the application and adjustment of the flexible body portion to the hair.

25 11. A hair curler, comprising a flexible body portion adapted to be rolled from its lower end in the hair, a hair clamp having hingedly connected arms for clamping the upper end of the flexible body portion to the hair, and means for separably connecting the clamp to the upper end portion of the flexible body portion to suspend the latter from the clamp during adjustment of the curler to the hair and to hold the flexible body portion from slipping downwardly after the clamp is applied to the hair.

NELL FULTON. 55
